UNITED STATES PATENT OFFICE.

LOUIS W. G. FLYNT, OF ROCHESTER, NEW YORK, ASSIGNOR TO UNITED SHOE MANUFACTURING COMPANY, OF PATERSON, NEW JERSEY, A CORPORATION OF NEW JERSEY.

IMITATION-STITCH MACHINE.

958,913.

Specification of Letters Patent. Patented May 24, 1910.

Application filed August 28, 1908. Serial No. 450,699.

To all whom it may concern:

Be it known that I, LOUIS W. G. FLYNT, a subject of the King of England, residing at Rochester, in the county of Monroe and State of New York, have invented certain Improvements in Imitation-Stitch Machines, of which the following description, in connection with the accompanying drawings, is a specification, like reference characters on the drawings indicating like parts in the several figures.

This invention relates to machines for operating upon the upper surface of the projecting edge of the sole of a shoe and is herein shown embodied in an imitation stitch machine.

The object of the present invention is to improve the construction and arrangement of the guards commonly employed in machines of this type for preventing the upper of the shoe from coming in contact with the stitch impression tool.

To this end a feature of the present invention consists in the provision of a guard comprising a casing arranged about the tool and a member arranged between the upper of the shoe and the tool and supported by said casing. With this arrangement the member between the upper and the tool may be made very thin and still be firmly sustained in working position, which is of advantage in that it allows the stitch impression tool to operate further beneath the bulging portion of the upper than would otherwise be the case. The member between the upper and the shoe is removably supported by the casing in order that it may be readily renewed when worn out.

Other features of the invention will be hereinafter described in the specification and pointed out in the claims.

In the drawings, —Figure 1 is a perspective view with parts broken away of a stitch impression machine provided with a guard embodying the present invention; Fig. 2 is a central longitudinal sectional view of the guard in working position; and Fig. 3 is a perspective view of the guard.

Referring to the drawings, 2 indicates a frusto-conical impression wheel of ordinary form which is removably secured on the end of a shaft 4 and arranged to act upon the projecting edge of a shoe sole, as indicated in Fig. 2. The main shaft 4 is mounted in bushings secured in the frame of the ma-

chine and is arranged to be rotated from a power shaft which carries fast and loose pulleys 6 and 8. For this purpose a gear 10, loosely mounted on the main shaft and restrained from longitudinal movement thereon, is arranged to mesh with a pinion, not illustrated, on the inner end of the power shaft. Motion is transmitted from the gear 10 to the main shaft by means of a clutch mechanism which comprises a circular member 12 splined on the main shaft and provided on its inner face with radial projections 14 adapted to interlock with a laterally projecting pin 16 on the gear 10 when the circular member is moved sufficiently inward.

A bell-crank lever is pivoted upon the frame of the machine at 18 and is arranged to move the circular member 12 into and out of operative relation with the gear 10. To this end an arm 20 of the bell-crank lever extends upwardly and is provided with a yoke having laterally projecting pins arranged to work in a peripheral slot in the circular member and a spring extending between the arm 20 and the frame of the machine serves to normally hold the circular member in operative position. The other arm 22 of the bell-crank lever may be actuated by a suitable treadle to throw the clutch mechanism out of operation.

The work is supported in engagement with the impression tool upon a rotary table 24 arranged upon a support 26. The support 26 is mounted for angular adjustment upon the end of a lever 28 which is pivoted upon a horizontal axis at 30. A piston 32, working in a cylinder 34 secured to the frame of the machine, serves to sustain the support 26. A rod 35 rigidly secured to the piston extends downwardly therefrom and is slidably mounted in a bushing 36 adjustably secured in the lower end of the cylinder. A coil spring 38 arranged in the cylinder between the piston and bushing serves to press the rotary table upwardly in order to hold the work in yielding engagement with the impression tool. The rod 35 is arranged to be actuated by a preliminary movement of the treadle to lower the rotary table in order to permit the insertion of the work between the impression tool and the table.

The above machine has been described in order to disclose the construction and arrangement of a well-known form of stitch

impression machine to which the present invention is adapted to be applied, but it will be understood that the invention hereinafter described is not limited for use with a machine similar to that above referred to.

In the present embodiment of the invention a tubular casing 40 is removably secured by a set-screw 42 upon one of the bushings, in which the main shaft is journaled and extends over the impression tool with its outer edge positioned back of the front face of the tool. A set screw 44, threaded into the frame of the machine, is arranged to be engaged by the tubular casing in order to limit inward movement of the latter and thus assist the operator in properly positioning the casing longitudinally of the tool. The lower front portion of the casing below its center is cut-away in order to expose the impression tool. As will appear from an inspection of the drawing, this portion is cut-away so as to form an opening which is defined by surfaces 46 extending rearwardly and upwardly in substantial parallelism with the lower surface of the impression tool, and a substantial vertical surface 48 which intersects the surfaces 46.

A thimble 50, formed of thin material, is removably fitted within the casing with its closed end arranged between the upper of the shoe and the impression tool, and a portion of the thimble below its center is removed by a cut extending rearwardly and upwardly to form an opening which registers with the opening in the casing. It will be seen that by forming the opening in the casing below its center the casing sufficiently surrounds the thimble to prevent any downward displacement of the latter.

A hollow screw 52 extending transversely through the casing and an opening in the thimble serves to prevent longitudinal displacement of the thimble. Upon unscrewing the screw 52, the thimble may be readily removed from the tubular casing. A stop 54, depending from the inner surface of the casing, serves to limit the inward movement of the thimble, and thus assist the operator in properly positioning the thimble within the casing. A flange 56 extending laterally from the stop 54 serves to assist in preventing downward displacement of the thimble. The impression tool is preferably heated, and for this purpose there is preferably provided a burner 58 which projects outwardly from the frame of the machine through a slot 60 extending longitudinally through the lower portion of the casing. The burner is supplied with gas in any suitable way.

It will be noted, in the construction shown, that the thimble may be formed of very thin material and still be firmly sustained in working position, which allows the tool to

operate farther beneath the bulging portion 65 of the upper than would otherwise be the case. When the thimble becomes worn out it may be replaced by a new one, and the provision of the stop 54 allows the operator to readily place the new thimble in the position occupied by the previous one, so that the thimble will be properly positioned in relation to the impression tool. Upon loosening the set screw 42, the tubular casing may be removed, when, for example, it is desired 75 to clean the impression tool or to substitute a new tool in place of the old one. The set screw 44 in the frame of the machine serves to assist the operator in replacing the casing in its original position.

Having described my invention, what I claim as new and desire to secure by Letters Patent of the United States is:

1. A machine of the class described, having in combination, a tool formed to operate 85 upon the upper surface of the projecting edge of the sole of a shoe, a stationary casing about the tool, and an inner shell removably fitted in said casing and having a thin wall arranged between the upper of the shoe and 90 said tool.

2. A machine of the class described, having in combination, a tool formed to operate upon the upper surface of the projecting edge of the sole of the shoe, a casing over 95 said tool with its outer end back of the front face of the tool and a member of thin material arranged between the upper of the shoe and said tool and removably secured in said casing.

3. A machine of the class described, having in combination, a tool formed to operate upon the upper surface of the projecting edge of the sole of a shoe, a stationary casing removably sustained about the tool and an 105 inner shell removably fitted in said casing and having a thin wall arranged between the upper of the shoe and said impression tool.

4. A machine of the class described, having in combination, a tubular member, a 110 shaft arranged to rotate therein and provided at its end with a rotary tool formed to operate upon the upper surface of the projecting edge of the sole of a shoe, a tubular casing arranged on said member with 115 its outer end back of the front face of the tool, and a member of thin material arranged between the upper of the shoe and said tool and removably sustained by said casing.

In testimony whereof I have signed my name to this specification in the presence of two subscribing witnesses.

LOUIS W. G. FLYNT.
